(57) **CLAIM**

The ornamental design for an personal tracker, as shown and described.

DESCRIPTION

FIG. 1 is an isometric view of the asset tracker

FIG. 2 is a front elevation view

FIG. 3 is a back elevation view

FIG. 4 is a left-side elevation view

FIG. 5 is a right-side elevation view

FIG. 6 is a top view

FIG. 7 is a bottom view

FIG. 8 is an isometric view of an alternative embodiment of the personal tracker

FIG. 9 is a front elevation view of an alternative embodiment

FIG. 10 is a back elevation view of an alternative embodiment

FIG. 11 is a left-side elevation view of an alternative embodiment

FIG. 12 is a right-side elevation view of an alternative embodiment

FIG. 13 is a top view of an alternative embodiment; and,

FIG. 14 is a bottom view of an alternative embodiment.

The broken line showing of structural features is included for the purpose of illustrating non-claimed subject matter and forms no part of the claimed design.
